UNITED STATES PATENT OFFICE

161,472

PROJECTILE-GAME BOARD

Carl Lapin and George Mysels, New York, N. Y.,
assignors to McKenzie Playthings, Inc., New
York, N. Y.

Application February 26, 1949, Serial No. 1,106

Term of patent 3½ years

(Cl. D34—5)

To all whom it may concern:

Be it known that we, Carl Lapin and George Mysels, both citizens of the United States, residing at New York, in the county of New York and State of New York, respectively, have invented a new, original, and ornamental Design for Projectile-Game Board, of which the following is a specification, reference being had to the accompanying drawings, forming part thereof.

In the drawings:

Fig. 1 is a perspective view of a projectile-game board showing our new design;

Fig. 2 is an exploded view thereof.

We claim:

The ornamental design for a projectile-game board, substantially as shown.

CARL LAPIN.
GEORGE MYSELS.
